UNITED STATES PATENT OFFICE.

BRADLEY HASKINS, OF MILWAUKEE, WISCONSIN, ASSIGNOR, BY MESNE ASSIGNMENTS,
TO ALLIS-CHALMERS MANUFACTURING COMPANY, A CORPORATION OF DELAWARE.

CIRCUIT-BREAKER.

1,177,948.

Specification of Letters Patent. Patented Apr. 4, 1916.

Application filed November 21, 1910. Serial No. 593,340.

To all whom it may concern:

Be it known that I, BRADLEY HASKINS, a citizen of the United States, residing at Milwaukee, in the county of Milwaukee and 5 State of Wisconsin, have invented certain new and useful Improvements in Circuit-Breakers, of which the following is a full, clear, and exact specification.

My invention relates to switches or circuit-breakers.

In circuit-breakers, which are usually caused to open upon the occurrence of some abnormal condition, it is desirable that it be impossible to close the circuit-breaker and 15 maintain it closed during the continuance of the abnormal condition.

It is the fundamental object of my present invention to provide such a circuit-breaker, and to do so by an arrangement 20 more simple and efficient than anything heretofore intended for the same purpose.

Among the other objects of invention are to provide an oil switch structure which is 25 removable as a unit from its oil tank and its operating and tripping mechanisms, and to improve the tripping mechanism.

There are provided two movable switch arms which are in series with each other when the switch is closed but are disconnected from each other when the switch is 30 open. Both of these arms must be in proper position in order for the switch to be closed; if either arm is in another position the circuit through the switch is broken. One of 35 the arms may be moved away from its closed position automatically upon the occurrence of a predetermined abnormal condition. This arm may be reset in its closed position only by means which at the same 40 time moves the other arm away from its closed position. The switch is not closed until the second arm is moved back to its closed position, whereupon, if the abnormal condition still continues, the first arm is immediately caused to move again to open 45 position.

Preferably the switch mechanism proper is so mounted that it is readily removable as a unit from the operating and tripping 50 mechanisms and the line connections, and also from the oil tank if the switch is an oil switch. The arrangement for tripping the circuit-breaker also contains several novel features, whereby the switch, if a multiple 55 switch controlling several lines, may be

tripped upon an abnormal condition in any-one of the lines, and may be adjusted for each line separately and for all the lines collectively.

The various novel features of my invention will appear from the description and drawings, and will be particularly pointed out in the claims.

Figure 1 is an end view of a switch or circuit-breaker embodying my invention, some 60 of the parts being shown in section and the switch being in closed position; Fig. 2 is a section through the same switch on the line 2-2 of Fig. 4, but shows the switch just after it has been automatically opened; Fig. 70 3 is a view somewhat similar to Fig. 1, showing the switch after it has been manually opened and with the switch unit proper partially raised from the tank; and Fig. 4 is a section mainly on the line 4-4 of Fig. 1. 75

The switch is shown as an oil switch of the switch-board type. The oil tank 10 is hung from a casting 11 supported on brackets 12 mounted on a panel 13 of the switch-board. Four rods 14 depend from 80 the casting 11, and at their lower extremities support two cross-bars 15 on which are mounted two parallel bars 16, of wood or other suitable insulating material, extending lengthwise of the switch near the bottom and carrying the switch terminals 17 and 17^a respectively. The switch shown being a three phase switch, there are three sets of terminals 17 and 17^a, the three terminals 17 being mounted on one bar 16 and 90 the three terminals 17^a on the other. The terminals 17 are connected to the line wires by conductors 18 and couplers 19, the connection extending from the inside to the outside of the tank through insulating bushings 20 in the casting 11. The terminals 17^a are connected to the line wires in a somewhat similar fashion, but the conductors between the terminals and the couplers, or some of them, are in the form of coils 21, 100 which are the overload coils of the circuit-breaker. The upper ends of the coils 21 are preferably mounted in castings 22, which are connected to the lower parts of the proper couplers 19 and mounted on a 105 bar 23, of wood or other suitable insulating material, in turn supported by nuts on two of the rods 14. The coils 21 are offset somewhat from the vertical planes of the corresponding sets of switch terminals. 110

The removable switch unit comprises the switch cover 24 provided with a lifting handle 25, and two end plates 26 and 27 depending from the cover 24 and cross-connected at their lower extremities by two bars 28 of wood or other insulating material. These bars 28 are firmly fastened to the end plates 26 and 27, and carry the fixed switch contacts 29 and 30. These contacts have 10 depending parts which normally engage the switch terminals 17 and 17^a respectively, with which they correspond in number and spacing. The two rods 31 and 32 are journaled in the end plates 26 and 27 and carry 15 the movable switch arms 33 and 34 respectively, which correspond in number and spacing with the pairs of contacts 29 and 30, there being three pairs in the switch illustrated. The arms 33 and 34 are 20 clamped around insulation 35 surrounding the rods 31 and 32, the cross-section of latter preferably being square between the end plates 26 and 27. The parts 17 and 17^a, 29 and 30, and 33 and 34 are all preferably 25 made of sheet metal, and are spaced so that corresponding pairs of switch terminals 17 and 17^a, fixed contacts 29 and 30, and switch arms 33 and 34 are all in the same vertical planes. The arms 33 and 34 are double 30 arms, their lower ends coöoperating with the fixed contacts 29 and 30 respectively while their upper ends coöperate with each other. Arcing tips 36 may be provided for either or both ends of the arms 33 and 34. The 35 switch is closed when the arms are in the positions shown in Fig. 1 and is open when they are in the positions shown in either Fig. 2 or Fig. 3.

On the ends of the rods 31 and 32 beyond 40 the end plate 27 are fixed double arms 37 and 38 respectively, to the upper ends of which are attached toggles 39 and 40 respectively, the other ends of these two toggles being pivoted on the end plate 27. 45 Links 41 and 42 connect the knees of these toggles to the ends of the beam 43, which has an upwardly extending arm 43^a carrying a pin 44 engaging a slot 45 in an end of a rod 46 extending to the operating handle 47. The link 42 is slotted at its connection with the toggle 40, so as to permit 50 a certain definite amount of lost motion between the two parts. The lower ends of the arms 37 and 38 are connected by a tension spring 48, which tends to open the switch by rotating the rods 31 and 32 in counter-clockwise and clockwise directions respectively. The rod 31, when in closed 55 position as illustrated in Figs. 1 and 2, is prevented from turning in response to such tendency by means of a latch 49 which engages the operating handle 47; this latch may be released by a push button 50 in such handle. The rod 32, when in closed position as shown in Figs. 1 and 3, is prevented

from turning in response to such tendency by the engagement of a roller 52 on an arm 53 with a notch in the end of an arm 54 fixed on one end of the rod 32. The arm 53, which is pivoted on the end plate 26, 70 is spring-pressed to hold the roller 52 in engaging position by means of a spring 55, the extent of its movement in this direction being adjustable by the limiting screw 56.

The arm 53 may be moved against the 75 spring 55 to release the arm 54 by my improved overload tripping mechanism. This tripping mechanism is as follows: A shaft 57 is mounted in bearings 58 fixed on the wooden bar 23. Fixed on this shaft opposite the upper end of the arm 53 is a hammer 59, in the end of which a roller 60 may be mounted to reduce friction. When the shaft 57 is turned in a counter-clockwise direction, the hammer 59 or its roller 60 strikes 80 the arm 53 to disengage the roller 52 from the arm 54. The shaft 57 may be biased in a clockwise direction by a light spring 61, the movement in this direction being limited, as will presently appear. Forked arms 62, 85 one for each overload coil 21, are also fixed on the shaft 57 in the same transverse vertical planes as the corresponding coils 21. The ends of the arms 62 are forked to accommodate guide rods 63 which extend 90 along the axes of the coils 21. These rods 63 may be of any suitable material, but are preferably made of metal where they are subject to friction, as at the end portions, and of insulating material in the central 95 portion; the joints between the metal and the insulating material are plainly shown in the drawings. The rods 63 extend through openings in the bar 23 and in the casting 11, and are supported at their upper 100 ends on arms 64 fixed on a shaft 65 mounted in bearings 66 on the casting 11. The connections between the rods 63 and their arm 64 are such that the rods may be turned on their axes by their handles 67, for 105 purposes hereinafter apparent. The shaft 65 may be rotated, to raise or lower the rods 63, by the handle 68 on the switch-board 13, this handle being connected to the shaft 65 by any suitable mechanism. The 110 lower ends of the rods 63 extend through holes in and are guided by a bar 70 of some suitable insulating material, such as wood, supported on two of the rods 14, and on the threaded lower portions of the rods 63, 115 just above the bar 70, are nuts 71. Slotted guides 72, supported on the bar 70 and engaging fingers projecting from the nuts 71, prevent such nuts from turning when the rods 63 are turned, so that turning one of 120 such rods raises or lowers its associated nut 71. The cores 73 of the overload coils 21 normally rest on the nuts 71. By adjustment of the handle 68 the normal positions of these cores may be adjusted collectively,

while by rotation of the handles 67 the normal positions of the individual cores 73 may be adjusted separately. When any core 73 is lifted by its associated coil 21, the 5 upper end of the core strikes the lower end of a spool-shaped sleeve 74, on the upper end of which the free ends of one of the arms 62 rest, and motion of the core is communicated through such sleeve and the arm 10 62 to the shaft 57 to rotate the latter in a counter-clockwise direction (Fig. 1) to strike the arm 53. The upper and lower flanges of the sleeves 74 limit the clockwise movement of the shaft 57 and the upward 15 movement of the cores 73 respectively.

The closed position of the circuit-breaker is shown in Fig. 1. Upon an overload in any one of the circuits through the switch, the proper overload coil 21 lifts its core 73 20 to tilt the shaft 57 and hammer 59 in a counter-clockwise direction, and the roller 60 on the hammer 59 strikes the upper end of the arm 53 and moves the roller 52 out of the notch in the arm 54, whereupon the 25 spring 48 turns the rod 32 and the arms 34 carried thereby in a clockwise direction to the position shown in Fig. 2. This breaks the circuit at both upper and lower ends of the arms 34, any arc which may form being 30 taken by the arcing tips 36. In order to close the circuit-breaker, the handle 47 must now be moved to the position shown in Fig. 3, the push button 50 being first depressed so that the latch 49 will allow such movement. 35 This movement of the handle 47 is communicated through the link 46, the beam 43, the links 41 and 42, the toggles 39 and 40, and the arms 37 and 38 to the rods 31 and 32, turning them both in a counter- 40 clockwise direction to the position shown in Fig. 3. This brings the rod 32, with its associated arms 34, into its closed position, or the same position in which it is shown in Fig. 1, in which position it is immediately 45 latched by the engagement of the roller 52 with the notch in the end of the arm 54. But this does not close the circuit through the circuit-breaker; for at the same time the rod 31 with its arms 33 is so moved that 50 the circuit remains broken at both the upper and lower ends of such arms. To close the circuit through the switch, the handle 47 must now be moved to the position shown in Fig. 1, this movement being communicated 55 to the rod 31 and the arms 33 to move them in a clockwise direction to the position shown in Fig. 1 and putting the spring 48 under tension. This closing movement of the handle 47 does not affect the rod 32 and its associated arms 34 because of the 60 lost motion permitted by the slot in the link 42. The rod 32 and its arms 34 are held in closed position by the engagement of the roller 52 with the notch in the end of the arm 54, unless an overload still exists; in

which case they are immediately tripped in the manner described above. It is thus impossible to maintain the circuit-breaker closed during the continuance of an overload.

To open the switch manually the push button 50 is depressed, whereupon the spring 48 moves the rod 31 and the arms 32 to a position such as shown in Fig. 3. When the parts are in this open position, and then 70 only, the removable switch unit may be removed or replaced, Fig. 3 showing it partly removed. Upon such removal, the parts carried by the cover 24 all pass upward through the opening in the casting 11. 80 The switch contacts 29 and 30 are separated from the switch terminals 17 and 17^a respectively, which remain in place. The operating mechanism also remains behind, the separation taking place in the manual 85 operating mechanism where the pin 44 engages the notch 45 and in the overload tripping mechanism between the roller 60 and the arm 53. The removal of the removable switch unit is prevented except 90 when the parts are as shown in Fig. 3, as then only can the pin 44 pass through the notch 75 in the inwardly extending flange 76 on the casting 11. At other times, such flange, by its engagement with the pin 44, 95 will prevent the upward movement of the cover 24 and the parts carried thereby. If desired, there may be a flange 76 with its notch 75 at each end of the casting 11, the beam 43 then being mounted on one end of 100 a shaft 77, on the other end of which is an arm 78 similar to the arm 43^a and carrying a pin 79 similar to the pin 44. The pin 79 co-operates with one of the flanges 76 and its notch 75. When the removable unit is put back in place, it may be fastened there by means of swing bolts 80 which engage 105 forked lips 81 on the edges of the cover 24.

With the arrangement described above it is impossible to maintain the circuit closed during the continuance of an overload. When the switch is tripped to open the circuit as shown in Fig. 2, it is necessary for the switch parts first to pass into the position shown in Fig. 3 (save for the elevation of the removable switch unit), and then to be brought to the position shown in Fig. 1. If the overload still continues, the switch 115 will immediately be tripped to bring the parts again to the position shown in Fig. 2. 120

Many modifications in the precise arrangement shown and described may be made without departing from the spirit and scope of my invention, and all such I aim to cover in the following claims.

What I claim as new is:

1. A switch comprising two movable toggle operated switch arms which are in engagement and in series when the switch 125 is closed and are disconnected from each 130

other when the switch is open, means for causing one of said arms to move from its closed position upon the occurrence of a predetermined abnormal condition, and means for restoring said arm to its closed position only by moving the other arm from its closed position.

2. In a switch, the combination of two movable switch arms having contacts at both ends, the contacts at one end engaging each other and being in series when the switch is closed, means responsive to an abnormal condition for causing the movement of one of said arms out of its engaging position, and means for restoring said arm to its engaging position only by moving the other arm out of the position in which it would engage the first.

3. In a switch, the combination of two movable switch arms having contacts at both ends, the contacts at one end being in series and in engagement with each other when the switch is closed and disconnected from each other when the switch is open, means tending to move one of said arms to open the switch, a latch for normally preventing such movement, means for tripping said latch upon the occurrence of an overload, and means for resetting the arm which moved upon such tripping only by moving the other arm out of its closed position.

4. In a switch, the combination of two movable switch arms having contacts at both ends, the contacts at one end engaging each other and being in series when the switch is closed, means tending to move one of said arms out of engagement with the other, a latch for preventing such movement, means for tripping said latch upon the occurrence of a predetermined abnormal condition, and means for resetting the arm which is moved upon such tripping only by moving the other arm out of its engaging position.

45. 5. In a switch, the combination of two movable switch arms having contacts at both ends, the contacts at one end being in series when the switch is closed and being disconnected from each other when the switch is open, means for causing one of said arms to move from its closed position upon the occurrence of a predetermined abnormal condition, means for restoring said arms to its closed position only by simultaneously moving the other arm from its closed position.

6. In combination, a receptacle, a switch comprising fixed and movable parts mounted in and removable from said receptacle, means tending to separate said switch parts when the same are in engagement, means for holding said switch parts in engagement against the tendency of said separating means, and automatic means mounted in

fixed relation to said receptacle for actuating said holding means to permit the separation of said switch parts, said switch parts being separable from said automatic means.

7. In a switch, the combination of two movable switch arms which are in series with each other when the switch is closed and are disconnected when the switch is open, means tending to move both of said arms to open said switch a latch for preventing the opening movement of one of said arms and automatic means for operating said latch means for moving the other switch arm to closed position, and a latch for holding the latter arm against movement from closed position.

8. In a switch, the combination of two movable switch arms which are in series with each other when the switch is closed and are disconnected when the switch is open, a spring bearing at each end on one of said arms and tending to move both of said arms to open said switch, two separate latches for preventing the opening movements of the two arms respectively, means for tripping one of said latches automatically and the other manually, and means for resetting the automatically tripped arm after it has been opened only by moving the other arm to open position.

9. In a switch, the combination of two movable switch arms which engage when the switch is closed, means tending to move both of said arms out of engaging position, a latch for preventing movement of one of said arms and automatic means for operating the same, means for positively operating said switch arms, and a latch for retaining said operating means to hold the second switch arm in closed position.

10. In a switch, the combination of two movable switch arms which engage when the switch is closed, means tending to move both of said arms out of engaging position, a latch for preventing movement of one of said arms and automatic means for operating the same, means for positively operating said switch arms, and a latch for retaining said operating means in position to hold the second switch arm in closed position, said operating means acting to reset the automatically tripped arm after it has been opened only by moving the manually tripped arm to open position.

11. In a switch, the combination of two movable switch arms having contacts at both ends, the contacts at one end being in series and in engagement with each other when the switch is closed and disconnected when the switch is open, means for causing the movement of one of said arms to open position upon the occurrence of a predetermined abnormal condition, and means which permits

such movement whenever the other arm is in closed position but which acts to move the first arm to closed position when the second arm is moved to open position.

5 12. In a switch, the combination of two movable switch arms having contacts at both ends, the contacts at one end engaging and being in series with each other when the switch is closed but disengaged when the switch is open, means for causing the movement of one of said arms out of its engaging position upon the occurrence of a predetermined abnormal condition, and means which permits such movement while 15 the other arm is in position for engagement but restores the first arm to its engaging position upon the movement of the second arm out of its engaging position.

13. A switch comprising two movable 20 switch arms having contacts at both ends, the contacts at one end being in series and in engagement with each other when the switch is closed and being disconnected from each other when the switch is open, means for 25 causing one of said arms to move from its closed position upon the occurrence of a predetermined abnormal condition, operating mechanism, and connections between said operating mechanism and said arms whereby 30 an initial movement of the operating mechanism restores to closed position the arm which was moved from closed position and also moves the other arm away from closed position, and a later movement of the 35 operating mechanism restores said latter arm to closed position.

14. In a switch, the combination of two movable switch arms having contacts at both ends, the contacts at one end engaging 40 each other and being in series when the switch is closed, means responsive to an abnormal condition for causing the movement of one of said arms out of its engaging position, and operating mechanism for moving 45 the second arm out of engaging position and restoring the first arm to engaging position and for later restoring the second arm to engaging position.

15. In a switch, the combination of two 50 movable switch arms having contacts at both ends, the contacts at one end being in series and in engagement with each other when the switch is closed and being disconnected from each other when the switch is 55 open, means tending to move one of said arms to open the switch, a latch for normally preventing such movement, means for tripping said latch upon the occurrence of an overload, operating mechanism, and connections between said operating mechanism and said two arms whereby the former resets the switch in closed position by first moving the second arm out of closed position and moving the first arm into closed

position and then moving the second arm 65 back to closed position.

16. In a switch, the combination of two movable switch arms having contacts at both ends, the contacts at one end engaging each other and being in series when the switch 70 is closed, means tending to move one of said arms out of engagement with the other, a latch for preventing such movement, means for tripping said latch upon the occurrence of a predetermined abnormal condition, 75 operating mechanism which when in closed position permits an opening movement of one of the arms when said latch is tripped, and by movement from closed position to open position and back to closed position 80 first moves the second arm to open position and the first arm to closed position and then moves the second arm back to closed position.

17. A switch comprising two movable 85 switch arms having contacts at both ends, the contacts at one end being in series and in engagement with each other when the switch is closed and being disconnected from each other when the switch is open, means 90 for causing one of said arms to move from its closed position upon the occurrence of a predetermined abnormal condition, and means for closing the switch by first moving the other arm out of closed position and 95 the first arm back to closed position and then moving the other arm back to closed position.

18. In a circuit breaker, a pair of oppositely disposed fixed contacts, a pair of oppositely disposed movable contact members, each of said movable contact members having a contact portion to engage one of said fixed contacts and a contact portion to engage a corresponding contact portion of the 100 other movable member, a latch for holding one of said members against movement from the position in which it engages the other member, and automatic means for tripping 105 said latch. 110

19. In a circuit-breaker, a pair of fixed contact members, a pair of movable contact members, each of said movable members being pivoted intermediate its ends and having at one side of said pivot a portion to engage a corresponding contact portion on the other member and at the other side of said pivot a portion to engage the corresponding fixed contact member, a latch for holding one 115 of said members against movement from the position in which it engages the other member, and automatic means for tripping said latch. 120

20. In combination, a receptacle, a switch mounted therein and comprising a movable contact member and a coöperating contact member to be engaged by said movable member, a latch for holding said contacts in 125

engagement, and automatic means within said receptacle for tripping said latch, said means being mounted in fixed relation to said receptacle, and said contact members 5 and said latch being mounted on a support and movable relatively to said receptacle and separable from said tripping means, whereby said switch parts can be removed as a unit from said receptacle independently 10 of said tripping means.

21. In combination, switch terminals fixed in position, a switch unit comprising relatively movable contact parts removably mounted in position, certain of said contacts being engageable with said switch ter- 15

inals, means for holding said contact parts in engagement, and automatic means fixed in position for actuating said holding means to permit the separation of said contact parts, said switch unit being movable into 20 and out of position wherein it co-operates with said switch terminals and said automatic means.

In testimony whereof I affix my signature, in the presence of two witnesses.

BRADLEY HASKINS.
